UNITED STATES PATENT OFFICE

152,269

DESIGN FOR A JEWELRY PIN

Daniel Kasoff, Brooklyn, N. Y., assignor to David
Grad Company, New York, N. Y., a firm

Application July 16, 1948, Serial No. 147,624

Term of patent 3½ years

(Cl. D45—19)

To all whom it may concern:

Be it known that I, Daniel Kasoff, a citizen of the United States, residing at Brooklyn, New York, in the county of Kings and State of New York, have invented a new, original, and ornamental Design for a Jewelry Pin, of which the following is a specification, reference being had to the accompanying drawing, forming part thereof.

In the drawing:

Fig. 1 is a front view of a jewelry pin showing my new design;

Fig. 2 is a rear view thereof; and

Fig. 3 is a side view thereof.

I claim:

The ornamental design for a jewelry pin, substantially as shown.

DANIEL KASOFF.
